United States Patent Office

Des. 187,769
Patented Apr. 26, 1960

187,769

DISPLAY CASE

Henry T. Parker, Grand Haven, Mich., assignor to Grand Haven Harbor Industries, Inc., Grand Haven, Mich., a corporation of Michigan

Application August 18, 1958, Serial No. 52,231

Term of patent 7 years

(Cl. 80—11)

Fig. 1 is a front perspective view taken from the left of a display case embodying my new design;

Fig. 2 is a rear perspective view thereof taken from the right; and

Fig. 3 is a front perspective view thereof taken from the top, the lower portion being broken away for convenience of illustration.

I claim:

The ornamental design for a display case, as shown.
